DOOR LATCHING MECHANISM

Waldemar A. Endter, Long Beach, Calif.

Application April 9, 1951, Serial No. 219,937

17 Claims. (Cl. 292—219)

1

This invention has to do with improvements in door latching and locking mechanisms of a type especially adaptable to automobile doors by reason of the particular operating and control characteristics of the mechanisms.

More particularly, the invention relates to locking and latching devices which may be described generally as comprising a holding assembly or mechanism to be carried by a door for control by so-called outside and inside operators, and embodying the combination of a bolt movable between latched and unlatched positions, and a cam mounted in spaced relation to the bolt. The stationarily or pillar mounted component of the latch device comprises a keeper structure mounted for reception between the bolt and cam parts of the door-carried holding mechanism so that in the latched condition of the parts, the keeper is held in dove-tail confinement between the bolt and cam.

The primary objects of the invention are directed to the embodiment in a holding mechanism and keeper combination thus characterized, of various novel features responsible for secure and efficient performance of the device under all operating conditions. Among the important objects is to adapt the mechanism for efficient take-up action, and specifically in a manner such that upon dove-tail reception of the keeper structure between the bolt and cam, the latter comes into such cooperation with the keeper structure as to produce a progressive take-up action tending to crowd the door to fully closed position and to effectively resist opening movement of the door from that position.

Preferably I employ a keeper structure comprising a housing containing a spring-urged rotatable keeper element positioned in the path of the bolt so that as the door closes, the keeper element engages and overrides the bolt to a position of confinement at what may be termed a rear side of the bolt. During the course of the bolt and keeper interengagement the cam is brought to act against the keeper structure, and preferably against a curved surface of its housing, in a manner such as to create a progressive and continuing reaction transmitted through the cam to the door-carried parts, and a corresponding closing take-up action on the door.

The type of bolt employed preferably is one mounted for oscillatory movement between latched and unlatched positions, and directly or indirectly spring-urged in a latching direction. Particularly contemplated is the provision of a holding element cooperating with the bolt nor-

2

mally to block its antilatching movement, and releasable by the inside or outside operators to free the bolt for release. As will appear, further controls may be used in association with the holding element, as to prevent its release from blocking relation with the bolt upon key controlled conditioning of the mechanism from the outside of the door, or upon setting of the garnish mold push button at the inside.

10 All the various features and objects of the invention, as well as the details of certain illustrative embodiments, will be made apparent from the following description of the accompanying drawings, in which:

15 Fig. 1 is a cross section taken through the door and pillar at their opposed edges, with the door fully closed and the latch mechanism parts appearing in plane;

20 Fig. 2 is a view taken from the plane of line 2—2 in Fig. 1, showing in elevation the door-carried holding mechanism with the keeper structure received between the bolt and take-up cam;

25 Fig. 3 is a view taken on line 3—3 of Fig. 1 illustrating the keeper structure in elevation;

Fig. 4 is a cross section on line 4—4 of Fig. 3;

Fig. 5 is a cross section on line 5—5 of Fig. 3;

30 Fig. 6 is a view similar to Fig. 2 showing the holding mechanism parts exposed within the case and in fully latched association with the keeper structure;

Fig. 7 is a section on line 7—7 of Fig. 6;

Fig. 8 is a fragmentary section on line 8—8 of Fig. 6;

Fig. 9 is a fragmentary section taken on line

35 9—9 of Fig. 6 and illustrating the push button connection with the blocking lever;

Fig. 10 is a cross section on line 10—10 of Fig. 6;

Fig. 11 is a fragmentary section on line 11—11 of Fig. 6 showing the key-actuated arm connection with the blocking lever;

Fig. 12 is a cross section on line 12—12 of Fig. 11;

Fig. 13 is a view showing certain of the holding mechanism parts in the positions assumed upon release of the bolt through actuation of the outside operator;

Fig. 14 is a view illustrating the relationship of certain of the parts upon partial opening of the door to a safety catch position;

Fig. 15 is a similar view showing the positions assumed by the parts upon movement of the bolt to unlatched position by the inside operator;

Figs. 16, 17 and 18 illustrate a progression of 55 the positions taken by the bolt, takeup cam and

keeper structure as the door closes from open to latched position;

Fig. 19 is a cross sectional view taken on line 19-19 of Fig. 21, illustrating a variational form of the invention;

Fig. 20 is a view of the keeper structure taken on line 20-20 of Fig. 19;

Fig. 21 is a view taken on line 21-21 of Fig. 19, showing certain of the holding mechanism parts at the inside of one flange of the door-carried case;

Fig. 22 is a view taken on line 22-22 showing the associated holding mechanism parts at the inside of a second flange of the case;

Fig. 23 is a cross section taken on line 23-23 of Fig. 21;

Fig. 24 is a cross section on line 24-24 of Fig. 22.

Fig. 25 is a section taken on line 25-25 of Fig. 23, and

Fig. 26 is a fragmentary view showing certain parts of Fig. 22 in changed positions.

Referring first to the form of the invention illustrated in Figs. 1 to 18, and particularly to the door and pillar assembly showing of Fig. 1, the latch mechanism comprises a holding mechanism, generally indicated at 25 contained by the swinging door 27, and specifically by application to its edge face 28, and a keeper structure, generally indicated at 29, stationarily applied to the edge face 30 of the usual door frame or pillar 31. The door and pillar are shown to carry cushions 32 and 33 which in the illustrated closed position of the door, bear respectively against the pillar and door shoulders 34 and 35. The hollow door structure is shown to contain the window glass 35 received and vertically movable within the channel-shaped glass run 36 carried by the inside of the metal edge piece 28. As illustrated in Fig. 1, the holding mechanism 25 is entirely free from interference with the glass window and its run, and is so positioned as to be controllable, in the manner later explained, by the outside push button operator mechanism generally indicated at 37, and the inside door handle mechanism generally indicated at 38.

Referring now to Figs. 3 and 4, the keeper structure 29 is shown to comprise a housing 39 containing a base plate 40 and attached to the pillar edge 30 by screws 41 with plate 40 confined between the pillar face and the housing flange 39a. The housing contains a keeper 42 mounted for pivotal movement on pin 43 terminating in plate 40 and at 44 in the outer wall of the housing. As illustrated, the keeper 42 projects out of the open bottom of the housing and has at 46 an arcuate shoulder extending about the arcuate edge 47 of the housing.

Keeper 42 is constantly urged in a direction of clockwise rotation as viewed in Fig. 3, by coil spring 48, one end of which terminates at 49 in the keeper, with the other terminal of the spring bearing against lug 50 struck out of the base plate 40. The keeper is rotatable between the limits of engagement between its shoulder 51 with edge 52 of the housing 39, and engagement of the end of the keeper slot 53 with the housing edge at 54. It may be observed at this point that the keeper edge 55 presents a curved surface engageable, as will appear, against the bolt, and that beyond this surface the keeper has a safety catch notch 56 cooperable with the bolt as explained hereinafter. Also it is noted that the housing 39 presents at 57 an arcuate surface engageable

progressively and smoothly by the later described take-up cam.

Referring now particularly to Figs. 2, 6 and 7, the holding mechanism 25 comprises a case 26 shaped to provide at 58 a recess for reception of the keeper structure 29 in the latched association of the parts appearing in Figs. 2 and 6. The top and bottom flanges 59 and 60 of the case are attached to the door edge 28 by screws 61. Referring to Figs. 6 and 7, the housing 26 contains a base plate 63 which, together with the outer wall of the housing 26, terminally receives the pivot pins 64, 65, 66 and 76. The extent of the base plate about the recess 28 and at 63a at the inside of the case flanges 59 and 60, appears clearly in Fig. 6.

The case contains a bolt 67 pivoted intermediate its ends on the pin 66 for movement between the latched and unlatched positions appearing respectively in Figs. 6 and 13. One end 67a of the bolt, presenting an outer curved face 68, an upper nose 69 and an inclined inwardly facing surface 70, is projectible up through opening 71 in the case adjacent the curved case wall 72 at the inside of the recess 58. The bolt has an inner extent or arm 67b presenting a curved edge 72, and a safety catch notch at 73. As illustrated by the dotted lines in Fig. 6, the thickness of the bolt arm 67b is reduced to provide at its far side a shoulder 74 for engagement by the spring urged setting crank generally indicated at 75, as will later appear.

The bolt 67 is urged for rotation in a clockwise direction about pin 66 as viewed in Fig. 6 by the setting crank 75 mounted for rotation about pin 76 terminating in the base plate 63 and housing 26, the crank being urged to rotate counterclockwise about the pin by coil spring 77 encircling the pin, one end of the spring bearing against the base plate lug 78 and the other end at 79 against the crank. The latter has an arm 80 bearing against the bolt shoulder 74 and thus tending to maintain the bolt in the latched position of Fig. 6, and a second arm 81 presenting a curved face 82.

Normally the bolt 67 is blocked against antilatching rotation by an outside operator actuated means including a holding lever 83 and a trigger element 83a, both pivotally mounted on pin 85. Element 83a is urged for clockwise rotation about the pin by coil spring 84 bearing at one end against the element lug 86. As illustrated in Fig. 6, by reason of the relative rotatability of arm 83 and element 83a, lug 86 is spaced from a surface 87 of the arm for reception of the upper end of the crank arm 81 so that curved surface 82 of the latter bears against the arm face 87. Near its lower end the trigger element 83a has a curved shoulder 88 engageable against the bolt surface 72a to block the bolt against antilatching rotation from fully latched position, and engageable also against the notch shoulder 73 to hold the bolt in a safety catch position, as will later appear. As best illustrated in Fig. 7, the upper end of the lever 83 is turned at 83a to extend through an opening 89 in the base plate 63 and door edge 28 for engagement by the outside operator 37. At this point it may be observed that upon counter-clockwise rotation about pin 65, arm 83 displaces the crank 75 against the resistance of spring 77, moving the arm shoulder 88 out of engagement with the bolt face 72a initially to the safety catch position appearing in Fig. 14, and finally to the fully releasing position as in Fig. 13.

The bolt 67 also is releasable to open or anti-latching position by a second or inside operator controlled lever 902 mounted for oscillation on pin 66 at the inside of the bolt, the right hand extent of the lever carrying a lug 91 engageable upwardly against the underside of the crank arm 80. The opposite end 901 is engageable by the nose 92 of a crank arm 93 pivoted on pin 64 and having at its lower end a pivotal connection 95 with strap 96 to be connected to the usual inside door handle, not shown, and comprising part of the mechanism indicated at 33 in Fig. 1. Thus upon actuation of the inside door handle to rotate arm 93 clockwise as viewed in Fig. 10, lug 91 engages and rotates the setting crank 75 clockwise against the resistance of its spring to an extent releasing the bolt to open position as illustrated in Fig. 15. It will be noted that the same rotation of the setting crank engages its arm 81 against lug 86 to rotate the trigger element 831 to the Fig. 15 released position and out of blocking association with the bolt.

Directly above recess 58, the case 26 contains a cam 98 pivoted on pin 90, the cam depending through opening 100 in the case and having a bottom curved camming surface 101 of progressively increasing radii counterclockwise about the axis of the pin 90. The cam is urged to rotate clockwise and into engagement with the keeper structure, and specifically the curved surface 57 of the housing 39, by a coil spring 102, one end of which bears against the base plate lug 103 and the other at 104 against edge 105 of the cam. As shown in Fig. 13, clockwise rotation of the cam under the influence of the spring, is limited by the cam engagement with the case shoulder 106 at the end of the opening 100.

Also mounted on pin 90 is a blocking lever 107 which in the course of its actuation, oscillates between the positions shown in Figs. 6 and 13, the lever being positively urged to the limits of those two positions by an over-center spring 108 one end of which terminates at 109 in the lever, and the other end at 110 in the base plate 63. Struck inwardly from arm 107a of the lever is a lug 111 which in the Fig. 6 position blocks the releasing lever 83, as will later appear. The terminal 112 of the lever arm 107a is received within opening 113 in an arm 114 associated with the later described key controlled parts. On its underside, arm 107a carries a lug 115 engageable by the cam edge 105. The opposite arm 107b of the blocking lever has a terminal 116, see Fig. 9, received within opening 117 in a lever 118 extending through opening 119 in the door edge and pivoted on pin 120 carried by the bracket 121. Lever 118 is connected at 122 to the usual push button rod 123 extending upwardly through the garnish mold of the door. In the solid line position appearing in Fig. 9, the push button rod 60 has been thrust down to swing lever 107 to the Fig. 6 position in which the lever-carried lug 111 is brought into the path of counterclockwise swinging of the lever extension 831 in slot 124, thus blocking lever 83 against counterclockwise rotation beyond the point of such engagement. As the push button rod is pulled up to the broken line position of Fig. 9, lever 107 is rotated counterclockwise to the Fig. 13 position, raising lug 111 above and out of the path of the lever extension 831.

Referring now to the outside operator mechanism as particularly illustrated in Figs. 1, 11 and 12, a polygonal cross section shaft 126 extending through opening 127 in the door handle 75

128, carries on its outer end a key tumbler cylinder 129, between which and the door face 130 is placed a coil spring 131 so that the shaft 126 is reciprocable longitudinally against the resistance of the spring by push button action upon exertion of finger pressure against the cylinder 129. The inner end of the shaft 126 extends through the correspondingly polygonal opening 132 in a bearing 133 rotatably carried within a bracket arm 134 extending inwardly from the door edge 23. The previously described arm 114 is carried by the bearing 133 for rotation therewith, that is, the shaft 126, bearing and arm 114 are rotatable together in response to turning of the shaft. As the shaft is pushed inwardly, its inner end engages the holding lever extension 831 to release the trigger 831 from blocking engagement with the bolt. Upon release of finger pressure against the cylinder 129, spring 131 returns the shaft to its illustrated position. Shaft 126 is rotatable by insertion and turning of a key within the cylinder 129, and as the shaft is rotated, the blocking lever 107 is oscillated between the two positions illustrated in Figs. 6 and 13.

In considering the operation of the mechanism, assume first the door to be closed with the parts positioned as in Fig. 6 and the push button rod 123 to be thrust down in its Fig. 9 solid position. In the resulting Fig. 6 position of the lever 107, lug 111 lies in the path of the lever extension 831 thus blocking bolt releasing rotation of lever 83 and element 831 in response to operation of the push button rod 126. By raising the push button rod 123 to the broken line position of Fig. 9, lever 107 is thrown to the Fig. 13 position so that movement of the outside operator 126 can rotate lever 83 in a bolt releasing direction. Depending upon the extent of the lever rotation, it may first be brought to the intermediate position of Fig. 14, in which the lever shoulder 88 engages in the safety catch notch 73 to hold the bolt in a partially released but still latching position in its holding relation with the keeper 42. Upon further rotation of the lever 83, the bolt 67 is permitted to drop to the fully opened position of Fig. 13. It will be noted that at the start of its bolt releasing rotation, the lever has a maximum distance of contact between pivot 65 and the point of engagement between surfaces 81 and 82, with resultant maximum mechanical advantage in overcoming the resistance of spring 77 to rotate the bolt setting crank 75. When the bolt is fully released, the parts assume their Fig. 13 position in which the keeper structure 29 is freed from its dove-tail retention between the bolt and cam 98, thus permitting the door to open. As the outside operator 126 is released, the parts restore to the Fig. 16 position.

From the foregoing it will be understood that a similar sequence of bolt releasing movements occurs upon actuation of the inside operator 93 causing lever 902 to rotate trigger 831 in a releasing direction through the intermediary and spring resistance of the crank 75. Fig. 15 illustrates the released condition of the parts upon full actuation of the inside operator. When the latter is released, the parts (except for lever 107) restore to their Fig. 6 positions.

Assume now the door to be open with the parts positioned as in Fig. 16. As the door is swung in a closing direction, face 68 of the bolt is engaged against the keeper surface 421, and as the bolt further advances to the Fig. 17 position, its nose 69 snaps into the safety catch notch 56 in the keeper to initially hold the door against re-

verse or opening movement. At about this point the keeper engages the bottom corner of the cam 98, and as the door continues to move inward and the keeper to override the nose of the bolt, the cam is displaced counterclockwise by the consequent rotation of the keeper element, an upper portion 42a of the keeper element engaging the cam at 98a to effect such cam displacement. At this point of overriding the nose of the bolt, the keeper is snapped counterclockwise by its 10 spring 48 downwardly against the bolt surface 70 to a latched position corresponding to Fig. 18. It is to be noted that the keeper housing surface 57 is engaged by the cam 98 in both Figs. 17 and 18 so that the keeper structure is held in dovetail relation with the cam and bolt in the safety catch position and all further latched positions beyond. As the parts assume their Fig. 18 position, the clockwise thrust of the cam against the keeper housing surface 57 tends to crowd the holding mechanism 29 and door to fully closed positions against the cushions 32 and 35 with a resultant take-up action represented by the travel of the keeper 42 down along the bolt surface 70 from the Fig. 18 position to that illustrated in Fig. 6. It is observed that together the cam edge surface 101 and bolt face 70 present an inwardly divergent or wedge shaped space or throat, and that as a result of the cam thrust against the keeper housing, the keeper structure is subjected to a squeeze between the cam and bolt surfaces, tending to produce a take-up displacement of the door and holding mechanism parts carried thereby.

It is important that the cam be positively displaced in the above manner during bolt overriding movement of the keeper element in order that the take-up action of the cam may occur after the keeper has moved into latched engagement with the rear face of the bolt. Unless the cam take-up action is thus delayed until after latching of the keeper and bolt, the full effect of the cam is not attained.

As will be evident from the foregoing, when the door is closed, the latch mechanism may be locked from the outside by key rotation of the shaft 126 and consequent rotation of arm 114 to swing lever 107 into the blocking position of Fig. 6. Corresponding blocking movement of the lever may result from operation of the push button rod 123 when it is desired to lock the door at the inside.

Upon occasions, the door may be swung from open to closed position with the blocking lever 107 in its Fig. 6 position as a result of prior locking of the parts by key at the outside, or by the push button rod at the inside of the door. Referring to Figs. 16 to 18, as it strikes the keeper housing surface 57, the cam is rotated into engagement with the blocking lever lug 115, following which continued counterclockwise rotation of the cam produces corresponding rotation of the lever 107 in displacing lug 111 to the Fig. 13 position, freeing lever 83 for actuation thereafter by the outside operator.

In Figs. 19 to 24 I show a variational form of the invention having essentially the same operating characteristics as the previously described embodiment, but differing primarily in its somewhat simpler construction and incorporation within the door, as distinguished from accommodation of the door-carried parts mainly outside the door edge as in Fig. 1.

Referring particularly to Figs. 19 to 21, the latch assembly comprises a keeper structure gen-

erally indicated at 140 carried by the inner face of the door pillar 141, and a holding mechanism generally indicated at 142 carried within the door 143 in opposed relation to the keeper structure. 5 As illustrated in Fig. 20, the keeper assembly 140 corresponds essentially to the keeper structure previously described and illustrated in Figs. 3 and 4. Briefly, the assembly may comprise the same form of housing 144 attached to the pillar by screws 145 and containing a keeper element 146 corresponding to the keeper 42 and urged by coil spring 147, see Fig. 20, to rotate in a clockwise direction.

As best illustrated in Figs. 19 and 21, the holding mechanism 142 comprises a support or case 148 including a flange 149 inside and paralleling the door edge 43, and a second right angle flange 150. Clamped between flange 149 and the door metal is the flange 151 of an open bottom housing 152, see Fig. 23, containing the take-up cam 153. The cam, corresponding in shape and function to the previously described cam 98, is carried by pin 154 and is rotatably urged thereon in a counterclockwise direction as viewed in the dotted line cam position of Fig. 21, by coil spring 155 terminally received within slot 156, the other end of the spring being received within a recess 157 in the cam, see Fig. 25. An arm 158 rotatably carried by the pin 154 at the inside of the case carries a lug 190 projecting with an arcuate recess 191 in the cam. When rotated counterclockwise from the Fig. 25 position, the cam engages the lug at 192 so that the lug and arm 58 are carried with the cam. Rotation of the cam under the influence of the spring is limited by the engagement of the cam with its housing at 193.

Below and in spaced relation to the cam, the case contains a pin 161 on which is pivotally mounted an arm plate 162 carrying a bolt lug 163 extending through and having its flange 163a secured to the inside of the plate 162. As illustrated in Figs. 21 and 23 the bolt 163 extends through and is capable of oscillation within a slot 164 in the door edge and case flange 149.

The bolt 163 and plate 162 normally are retained in their keeper latching positions of Fig. 21 by crank element 166 pivotally carried by pin 167 and urged by coil spring 168 to rotate clockwise about the pin, one end of the spring bearing at 169 against the retaining element and the other at 170 against lug 171 struck out of the case. The element 166 comprises an arm 172 having shoulder 173 engageable by the lower corner 174 of plate 162, normally to positively hold the bolt 163 in latching position. Beyond shoulder 173, the arm contains a notch 175 for reception of the plate corner 174 in a safety catch position of the parts, reached upon partial release of the bolt from full latching position. The element 166 then carries a second arm 176, the nose 177 of which is engageable against arm 178 of a control plate 179.

The latter is mounted for oscillation on pin 161 and carries a flange 179a engageable by the diagrammatically indicated longitudinally reciprocable outside operator or push button rod 180. An over-center spring 181 terminally connected at 182 and 183 respectively to the plate 179 and case, serves to positively throw the plate to the limits of its oscillation about the pin 161. Normally the plate is stopped against counterclockwise rotation relative to the bolt plate 162 by engagement of lug 184 carried by plate 179 and engageable against the edge of plate 162. Plate

179 has also an arm 185 having a turned end 186, the purpose of which will presently appear.

As will be understood from the first described form of the invention, as the door-carried assembly of Fig. 21 is swung toward the left against the keeper structure 140 designated by the dotted lines in Fig. 21, the keeper element 146 overrides the bolt 163, first to the safety catch position, and then to the progressive latched positions beyond. Simultaneously, the upper face 146a of the keeper element engages against the cam face 153a, rotating the cam against the resistance of its spring 155 until the cam overrides the keeper housing 144, whereupon the cam starts and continues to exert its take-up thrust, the reaction to which results in progressive take-up action and closing of the door.

Referring now to the control mechanism shown in Figs. 22 and 26, a longitudinally reciprocable link 200 to be operated by the inside door handle, not shown, is pivotally connected at 201 of the arm 202 of a lever 203 pivotally mounted at 204. The opposite arm 205 of lever 203 has a terminal 206 engageable with the previously described lug 183 to release the bolt 163 from latched condition, as will later appear. The arm 205 carries a depending projection or arm portion 207.

The control mechanism also includes a vertically shiftable link 208 guided by pins 204 and 209 extending respectively through slots 210 and 211 in the link. The latter contains at its upper end a notch 212 which receives arm 158 so that the link and arm are interengaged for movement together. Provision is made for positively throwing the link toward the limits of its vertical travel as defined by the engagement of pins 204 and 209 with the ends of slots 210 and 211, by means of an over-center spring 213, the ends of which are connected respectively to the link and case flange 150.

The control mechanism also includes a rotor 214 mounted between flange 150 and a housing plate 215, the rotor to be actuated by key controlled turning outside the door of a shaft receivable within opening 216 in the rotor hub. The rotor carries a plurality of arms, the first 217 of which is receivable within a recess 218 in the link 208, so that the arm and link are in effect geared for movement together. The rotor carries a second arm 219 engageable with a curved camming surface 220 on the arm 202, and a third arm 221 underlying arm 207 as viewed in Fig. 2 and adapted to be swung beneath and in blocking relation to lug 186, as illustrated in Fig. 26.

In considering the operation of the latch mechanism shown in Figs. 19 to 26, assume the keeper structure to be held in latched condition between the cam and bolt as shown in Fig. 21, and the control mechanism parts to be positioned as in Fig. 22. As previously described, the bolt 163 may be released by actuation of the outside operator 180 and resultant rotation of the lever 186 and arms 176 and 172. The bolt may also be released by movement toward the right of link 209 in Fig. 22, resulting in movement of the arm terminal 206 downwardly against lug 186, causing bolt releasing rotation of lever 183 and arms 176 and 172 in the same manner as response to actuation of the outside operator 180.

Assume next that it is desired to lock the door in closed position. Upon key turning of the rotor 214 clockwise, arm 221 is swung beneath lug 186, see Fig. 26, thus blocking lever 185 against bolt releasing rotation. Counterclockwise rotation of the rotor 214 is accommodated

by upward shifting of the link 208 and rotation of the arm 158.

Next, assume the door to be open with the parts in the locked condition of Fig. 26 and that the door is to be closed. As the keeper element 146 strikes against the bolt 163, the keeper element is rotated into engagement with the cam shoulder 153a, producing rotation of the arm 158 and downward shifting of the link 208. Through its connection at 217, 218 with the link, the rotor 214 is turned clockwise from its Fig. 26 position and restored to the Fig. 22 condition, thus all in a manner such that restoration of the holding mechanism from locked to unlocked condition occurs as a result of closing interengagement of the latch mechanism parts.

Finally assume the mechanism to be engaged in fully latched condition and that it is desired to lock the door at the inside by actuation of the link 200. Upon shifting of the latter to the left as viewed in Fig. 22, the rotor arm 219 is engaged by cam surface 220 on the lever arm 202 and the rotor is turned counterclockwise to a position corresponding to that of Fig. 26 in which the rotor arm 221 is swung beneath and in blocking relation to the lug 186.

I claim:

1. A latch device comprising a holding mechanism to be carried by a first member and comprising a bolt movable between latched and unlatched positions, retaining means releasably maintaining said bolt in latched position, a cam movable in take-up and anti-take-up directions and positioned in spaced relation to said bolt, means for releasing said holding means; and a keeper structure to be carried by a second member movable relative to said first member and positioned for reception in dove-tail relation between and in engagement with said cam and bolt, 30
2. A latch device comprising a pivotally movable latching keeper element deflectible by engagement with a forward face of the bolt as one of said members moves relative to the other to override the bolt and then engage a rear face of the bolt, said cam having a surface progressively bearing against said keeper structure upon movement of the cam in said take-up direction, said cam being positioned in the path of said keeper element at a location to be displaced thereby in anti-take-up direction upon such deflection of the keeper element by the bolt and to be held in displaced position during said overriding of the bolt by the keeper element, and said cam then moving in said take-up direction to exert against the keeper structure a thrust tending to urge said holding mechanism and said keeper structure relatively together in a final closing movement, said keeper element having a shoulder engageable with a shoulder on the cam to displace the cam in said anti-take-up direction, 45
3. A latch device as claimed in claim 1, comprising means mounting said cam for pivotal movement, and a spring urging the cam in said take-up direction and against the keeper structure, 50
4. A latch device as claimed in claim 1, comprising means constantly urging said bolt toward latched position, 55
5. A latch device comprising a holding mechanism to be carried by a first member and comprising a bolt movable between latched and unlatched positions, retaining means releasably maintaining said bolt in latched position, a cam movable in take-up and anti-take-up directions and positioned in spaced relation to said bolt, 60

11

latched positions, retaining means releasably maintaining said bolt in latched position, a cam movable in take-up and anti-take-up directions and positioned in spaced relation to said bolt, means for releasing said holding means; and a keeper structure to be carried by a second member movable relative to said first member and positioned for reception in dove-tail relation between and in engagement with said cam and bolt, said keeper structure comprising a housing and a pivotally movable latching keeper element partially contained within the housing and deflectible by engagement with a forward face of the bolt as one of said members moves relative to the other to override the bolt and then engage a rear face of the bolt, said cam having a surface progressively bearing against said keeper structure upon movement of the cam in said take-up direction, said cam being positioned in the path of said keeper element at a location to be displaced thereby in anti-take-up direction upon such deflection of the keeper element by the bolt and to be held in displaced position during said overriding of the bolt by the keeper element, and said cam then moving in a take-up direction to exert against the keeper housing a thrust tending to urge said holding mechanism and said keeper structure relatively together in a final closing movement, said keeper element having a shoulder engageable with a shoulder on the cam to displace the cam in said anti-take-up direction as the keeper element overrides the bolt.

6. A latch device as claimed in claim 5, comprising means mounting said cam for pivotal movement, and a spring urging the cam in said take-up direction and against said keeper housing.

7. A latch device as claimed in claim 5, comprising a spring urging the cam in said take-up direction and against said keeper housing.

8. A latch device comprising a keeper structure to be carried by a door pillar and comprising a pivotally movable keeper element, a holding mechanism to be carried by a swinging door and comprising a bolt, means pivotally mounting the bolt for movement between latched and unlatched positions, a movable take-up cam movable in take-up and anti-take-up directions and positioned in spaced relation to the bolt, said keeper structure being positioned for reception between the bolt and cam in dove-tail relation as the door closes and said keeper element being deflectible by engagement with a forward face of the bolt as the door closes to override the bolt and then engage a rear face of the bolt, said cam having a surface progressively bearing against said keeper structure upon movement of the cam in said take-up direction, said cam being positioned in the path of said keeper element at a location to be displaced thereby in anti-take-up direction upon such deflection of the keeper element by the bolt and to be held in displaced position during said overriding of the bolt by the keeper element, said cam then moving in a take-up direction to exert against the keeper structure a thrust tending to urge said holding mechanism and door in a final door closing movement, movable holding means engageable with said bolt to positively maintain the bolt in latched position, and means for releasing said holding means, said keeper element having a shoulder engageable with a shoulder on the cam to displace the cam in said anti-take-up direction.

9. A latch device as claimed in claim 8, com-

12
prising a spring constantly exerting a force urging said bolt toward latched position.

10. A latch device comprising a keeper structure to be carried by a door pillar and comprising a pivotally movable keeper element, a holding mechanism to be carried by a swinging door and comprising a bolt, means pivotally mounting the bolt for movement between latched and unlatched positions, a cam movable in take-up and anti-take-up directions and positioned in spaced relation to the bolt, said keeper structure being positioned for reception between the bolt and cam in dove-tail relation as the door closes and said keeper element being deflectible by engagement with a forward face of the bolt as the door closes to override the bolt and then engage a rear face of the bolt, said cam having a surface progressively bearing against said keeper structure upon movement of the cam in said take-up direction, said cam being positioned in the path of said keeper element at a location to be displaced thereby in anti-take-up direction upon such deflection of the keeper element by the bolt and to be held in displaced position during said overriding of the bolt by the keeper element, said cam then moving in a take-up direction to exert against the keeper structure a thrust tending to urge said holding mechanism and door in a final door closing movement, movable holding means engageable with said bolt to positively maintain the bolt in latched position, a pivotal bolt setting member engageable with the bolt, a spring urging said member to maintain said bolt in latched position, and means for releasing said holding means against the resistance of said setting member, said keeper element having a shoulder engageable with a shoulder on the cam to displace the cam in said anti-take-up direction.

11. A latch device comprising a keeper structure to be carried by a door pillar and comprising a pivotally movable keeper element, a holding mechanism to be carried by a swinging door and comprising a bolt, means pivotally mounting the bolt for movement between latched and unlatched positions, a cam movable in take-up and anti-take-up directions and positioned in spaced relation to the bolt, said keeper structure being positioned for reception between the bolt and cam in dove-tail relation as the door closes and said keeper element being deflectible by engagement with a forward face of the bolt as the door closes to override the bolt and then engage a rear face of the bolt, said cam having a surface progressively bearing against said keeper structure upon movement of the cam in said take-up direction, said cam being positioned in the path of said keeper element at a location to be displaced thereby in anti-take-up direction upon such deflection of the keeper element by the bolt and to be held in displaced position during said overriding of the bolt by the keeper element, said cam then moving in a take-up direction to exert against the keeper structure a thrust tending to urge said holding mechanism and door in a final door closing movement, movable holding means engageable with said bolt to positively maintain the bolt in latched position, means for releasing said holding means, and a member movable into and out of a position blocking said holding means against bolt releasing movement, said keeper element having a shoulder engageable with a shoulder on the cam to displace the cam in said anti-take-up direction.

12. A latch device comprising a keeper structure to be carried by a door pillar and comprising

13

a pivotally movable keeper element, a holding mechanism to be carried by a swinging door and comprising a case containing a recess for reception of said keeper structure, a bolt movably mounted at one side of the recess for movement between latched and unlatched positions, a cam movable in take-up and anti-take-up directions and positioned in spaced relation to the bolt at the opposite side of said recess, said keeper structure being positioned for reception between the bolt and cam in dove-tail relation as the door closes and said keeper element being deflectible by engagement with a forward face of the bolt as the door closes to override the bolt and then engage a rear face of the bolt, said cam having a surface progressively bearing against said keeper structure upon movement of the cam in said take-up direction, said cam being positioned in the path of said keeper element at a location to be displaced thereby in anti-take-up direction upon such deflection of the keeper element by the bolt and to be held in displaced position during said overriding of the bolt by the keeper element, said cam then moving in a take-up direction to exert against the keeper structure a thrust tending to urge said holding mechanism and door in a final door closing movement, movable holding means engageable with said bolt to positively maintain the bolt in latched position, and means for releasing said holding means, said keeper element having a shoulder engageable with a shoulder on the cam to displace the cam in said anti-take-up direction.

13. A latch device comprising a holding mechanism to be carried by a first member and comprising a bolt movable between latched and unlatched positions, retaining means releasably maintaining said bolt in latched position, and a movable element positioned in spaced relation to said bolt; and a keeper structure to be carried by a second member movable relative to said first member and positioned for reception in dovetail relation between and in engagement with said bolt and element, said keeper structure including means engageable with a rear face of said bolt to hold the keeper structure and bolt against relative separating movement, said element being positioned at a location to be engaged and displaced by said keeper structure as said structure moves into said dovetail relation between the bolt and element, said device including movable unlocking means for releasing said bolt retaining means to permit movement of the bolt to said unlatched position, said element and said unlocking means having shoulders interengageable to actuate the unlocking means and thereby release the bolt retaining means upon said displacement of said element by the keeper structure.

14. A latch device comprising a holding mechanism to be carried by a first member and including a bolt movable between latched and unlatched positions, and retaining means releasably maintaining said bolt in latched position; and a keeper structure to be carried by a second member movable relative to said first member and including a pivotally movable latching keeper element deflectible by engagement with a forward face of the bolt as the members move together

14

to override the bolt and then engage a rear face of the bolt, said device including a movable part positioned at a location to be engaged and displaced by said keeper element upon said deflection of the keeper element by the bolt, and including movable unlocking means for releasing said bolt retaining means to permit movement of the bolt to unlatched position, said part and said unlocking means having shoulders interengageable to actuate the unlocking means and thereby release the bolt retaining means upon said displacement of said part by the keeper element.

15. A latch device as recited in claim 14 in which said movable part is positioned in spaced relation to said bolt, and said keeper structure is positioned for reception in dovetail relation between and in engagement with said bolt and said movable part.

16. A latch device as recited in claim 15 including a spring yieldingly resisting said displacement of the movable part, said keeper structure including a keeper housing against which said movable part bears in closed condition of the device.

17. A latch device comprising a holding mechanism to be carried by a first member and comprising a bolt movable between latched and unlatched positions, retaining means releasably maintaining said bolt in latched position, cam means movable in take-up and anti-take-up directions and positioned in spaced relation to said bolt, means for releasing said holding means; and a keeper structure to be carried by a second member movable relative to said first member and positioned for reception in dovetail relation between and in engagement with said cam means and bolt, said keeper structure comprising a pivotally movable latching keeper element deflectible by engagement with a forward face of the bolt as one of said members moves relative to the other to override the bolt and then engage a rear face of the bolt, said cam means having a surface progressively bearing against said keeper structure upon movement of the cam means in said take-up direction, said keeper element having a shoulder engageable with a shoulder on said cam means and acting to displace said cam means in anti-take-up direction upon such deflection of the keeper element by the bolt and to hold the cam means in displaced position during said overriding of the bolt by the keeper element, and said cam means then moving in said take-up direction to exert against the keeper structure a thrust tending to urge said holding mechanism and said keeper structure relatively together in a final closing movement.
